UNITED STATES PATENT OFFICE.

THOMAS WILLIAM LOWE, OF WINNIPEG, MANITOBA, CANADA.

TUBE AND SHEET CONNECTION.

Application filed November 1, 1921. Serial No. 511,974.

My invention relates to tube and sheet connections particularly useful for the attachment of water circulation tubes to the tube sheets of locomotive fire boxes. The invention is of especial advantage in fire boxes with very shallow throat sheets (particularly those of the Wooten type), affording a novel attachment of the arch supporting water tubes in such a fire box to the flue sheet itself 5 above the throat sheet, high enough to give the tubes a practical firing clearance above the grate.

How these and still other advantages can be obtained through my invention will appear from my description hereinafter of the best embodiment known to me.

In the drawings, Figure 1 shows a vertical longitudinal section through a boiler fire box of the locomotive type with an arch supporting tube secured to the flue sheet above the throat sheet in accordance with my invention.

Figure 2 shows an enlarged section through the tube and its joint with the flue sheet.

Figure 3 is a fragmentary view, similar to Figure 1, but on a larger scale, showing the attachment of a tube to the tube sheet in accordance with my invention.

In Figure 1 is shown a locomotive type boiler 4 with quite shallow throat sheet 5. In the fire box 6 is an arch of fire brick 7 supported on fore and aft water circulation tubes 8 that are connected to the rear wall 9 of the fire box above the fire door 10, in the usual way. The forward ends of the tubes 8, however, are not connected to the flue sheet below the shallow throat sheet 5, as is usual, but are bent upward slightly at 11 and attached to the flue sheet 12, —above the throat sheet, but below the fire tubes 13. As shown, this connection is not made by expanding the tubes 8 in the sheet 12 as usual, —as at the inner door sheet 14, —but in the novel manner illustrated in Figure 2.

As shown in Figure 2, the end of each tube 8 is externally enlarged at 15, by upsetting, and is also externally flanged at 16. The flange 16 is seated and secured in a bevel edged recess or depression 17 in the rear side 50 of the sheet 12, around a hole 18 therein that

coincides, in both size and position, with the inside of the tube 8. The flange 16 may be secured to the sheet 12 (which is in effect a tube sheet in reference to the tubes 8) by welding. As shown, the front face of the flange 16 may be autogenously welded to the bottom of the recess 17, as by spot-welding; and its bevel-edged periphery may be fusion-welded to the peripheral wall of the recess by means of interposed added metal 20. As illustrated, this added metal 20 is also fused and welded about the tube 8 over the flange 16, at 21, so as to reinforce and stiffen the tube and its connection to the sheet 12 at this point, and to afford protection against burning of the joint in service.

Welding of the tubes 8 to the rear side of the sheet 12 obviates all necessity for the presence of plugged openings opposite the forward ends of the tubes, —such as would be necessary if the tubes had to be expanded in the sheet 12 when being installed or replaced, —and is thus important in enabling the tubes to be attached, as shown, above the throat sheet 5, where openings could not well be provided. Such a relatively high location of the forward ends of the tubes 8 is of importance in affording a practical firing clearance beneath the tubes above the grate, especially in boilers with such shallow throat sheets as are characteristic of the Wooten type.

In Fig. 3, the forward ends of the tubes 28 are shown as sloping downward unbent and attached to the tube sheet 5 in the manner illustrated in Figure 2. Though not required for installation or replacement of the tubes 28, openings with screw threaded clean-out plugs 29 are provided in the outside sheet 30 opposite the tube ends.

I claim:

1. The combination with a tube sheet, of a tube with external flange seated and welded in a lateral recess in the face of said sheet whence said tube extends.
2. The combination with a tube sheet, of a tube with external flange seated and peripherally welded in a lateral recess in the face of said sheet whence said tube extends.
3. The combination with a tube sheet, of

a tube with external flange seated and welded in a lateral recess in the face of said sheet whence said tube extends, with a protecting reinforcement welded about said tube over 5 said flange at the same side of the sheet.

4. The combination with a tube sheet, of a tube with external flange seated in a lateral

recess in the face of said sheet whence said tube extends, said flange being secured in the sheet and reinforced and protected at its rear 10 by a fusion weld of added metal.

In testimony whereof I have hereunto signed my name.

THOMAS WM. LOWE.
